CLAIM

The ornamental design for a fan part, as shown and described.

DESCRIPTION

FIG. 1 is a perspective view of a fan part.

FIG. 2 is a right side elevation view of FIG. 1.

FIG. 3 is a left side elevation view of FIG. 1.

FIG. 4 is a front elevation view of FIG. 1.

FIG. 5 is a bottom plan view of FIG. 1; and,

FIG. 6 is a top plan view of FIG. 1.

The dashed lines illustrate portions of the fan part that form no part of the claimed design.
